E. KIRIAK

INCANDESCENT LAMP

Filed Nov. 28, 1922

FIG. 1

FIG. 2

FIG. 3

Inventor
Emery Kiriak

By

John A. Polachek
Attorney

UNITED STATES PATENT OFFICE.

EREMY KIRIAK, OF FORD, ONTARIO, CANADA.

INCANDESCENT LAMP.

Application filed November 28, 1922. Serial No. 603,742.

To all whom it may concern:

Be it known that I, EREMY KIRIAK, a citizen of Canada, residing at Ford, in the Province of Ontario and Dominion of Canada, have invented certain new and useful Improvements in Incandescent Lamps, of which the following is a specification.

This invention relates to incandescent lamp having for a general object the provision of a multiple filament lamp.

Other objects relate to the mounting of the filament and to the provisions of parallel connections or arrangements for a single filament whereby the latter serves as a multiple filament, the various sections of the single filament being electrically independent of one another.

For further comprehension of the invention, and of the objects and advantages thereof, reference will be had to the following description and accompanying drawings, and to the appended claims in which the various novel features of the invention are more particularly set forth.

Fig. 1 of the drawings is a perspective view of an incandescent lamp constructed according to the invention.

Fig. 2 is a partial central longitudinal sectional view thereof.

Fig. 3 is a detail perspective view of one of the filament holding members.

Referring now to the drawings 10 indicates a glass bulb of usual form which is set in the usual plastic material 11 in the threaded base 12. Extending centrally through this bulb is a glass tube 13 whose outer end is inturned to engage over a frusto-conical neck 14 projecting from a disk-like head 15. Soldered or otherwise secured to this head 15 is a disk 16 having a number, preferably five, of integral radial arms 17 over the ends of which a filament 18 is looped.

Adjacent the base of the lamp the tube 13 is bulged outwardly as at 20 to provide a shouldered element on which sits a disk 21 having a number of integral radial arms 22 to receive the filament 18. The disk 21 has a central aperture 23 which receives the tube 13. In the making of the parts a narrow tongue 24 is struck from the disk 21 previous to the forming of the aperture 23 and previous also to the securing to the underside of the disk of a circular, interiorly screw-threaded flange 26 which may be soldered in place. Engaged in this flange 26

is an exteriorly threaded flange 27 projecting upwardly from an apertured member 28 which sits against the lower face of the bulged element 20.

The tongue 24 extends downwardly outside the flange 26 and is carried through a suitable aperture in the neck of the bulb and soldered at its end to the base member 12. The base of the lamp has mounted thereon the usual central contact element 30 and a wire 31 is extended down the tube 13 and soldered at opposite ends to the disk 16 and to this element 30.

The filament 18 is looped around the upper and lower sets of arms 17 and 22 and in order to cause individual lengths or sections of the filament to remain attached to the arms in the event of rupture of the filament at some point the ends of said arms are bent as at 17' and 22' to form V-notches in which the filament is wedged with sufficient force to hold it in place.

As will be apparent, the various sections of the filament are connected in parallel, thus in effect producing a multiple filament, and in the event of rupture of one section current will flow as usual through the remaining sections.

My invention is designed more particularly for embodiment in lamps of low voltage, such as six to eight volts, although I do not limit the application of the invention to such lamps. It will also be understood that while I have illustrated and described a preferred embodiment of the invention I do not limit myself to the exact construction herein disclosed and that various changes and modifications might be made without departing from the spirit and scope of the invention as defined in the appended claims.

Having thus described my invention what I claim as new and desire to protect by Letters Patent of the United States is as follows:

1. In an incandescent lamp, a filament support comprising an elongated member having a circumferential shoulder formed thereon, a disk resting on said shoulder and having a depending exteriorly screw-threaded flange, an element engaging the lower face of said shoulder and having an upwardly projected annular flange screwed into the first flange, and a series of arms radiating from said disk and adapted to have a filament looped thereover.

2. In an incandescent lamp, a bulb, a base in which said bulb is set, a tube extending centrally through the said bulb and formed with a circumferential shoulder, a disk clamped upon said shoulder and having a number of arms radiating therefrom and adapted to have a filament looped there- over, and an integral tongue radiating from said disk and engaged with said base to form the electrical connection between the filament and the base. 10

In testimony whereof I have affixed my signature.

EREMY KIRIAK.
